UNITED STATES PATENT OFFICE.

HENRY B. PITNER, OF LA PORTE, INDIANA.

CARPET STRETCHER AND TACKER.

SPECIFICATION forming part of Letters Patent No. 394,934, dated December 18, 1888.

Application filed November 17, 1887. Serial No. 255,399. (No model.)

To all whom it may concern:

Be it known that I, HENRY B. PITNER, a citizen of the United States, residing at La Porte, in the county of La Porte and State of Indiana, have invented certain new and useful Improvements in Carpet Stretchers and Tackers; and I do declare the following to be a full, clear, and exact description of the invention, such as will enable others skilled in the art to which it appertains to make and use the same.

My invention relates to carpet-stretchers; and it consists in the novel construction hereinafter specified, whereby a carpet may be readily and effectively stretched to the position desired and the same automatically tacked to the floor.

The invention will be fully understood from the following description and claims when taken in connection with the annexed drawings, in which—

Figure 1 is a perspective view of my improved carpet stretcher and tacker. Fig. 2 is a sectional view of the same, taken on the line xx of Fig. 1; and Fig. 3 is a sectional detail view.

Referring to the said drawings by letter, A indicates a block preferably provided with a leather bottom, a , and a front metallic plate, c .
30 Passing through the bottom a and into the block is a series of teeth, b , arranged in diagonal positions, as shown in Fig. 1 of the drawings.

B indicates a handle, which is rigidly attached to the rear end of the block A in any suitable manner.

C represents a trip-hammer, the rear end of which is pivoted in the brackets or ears D. Said brackets are rigidly secured to the upper 40 face of the block A. A spring is coiled around the pivot-pin or shaft of the hammer and outside the upright portions of the brackets D, both to the right and left of the hammer, as shown on Fig. 1, the middle portion, f , resting 45 against the curved rear end of the hammer, as also shown on Fig. 1.

G represents a tube, preferably formed of two sections arranged in the front end of block A and with projecting ears at their 50 tops, which are united by means of coiled springs h .

It is obvious that when the hammer passes

down into this tube the sections will be forced apart at the bottom, and also that when the hammer is withdrawn the spring h will retract the sections so as to leave a small opening at the extreme lower point of the tube.

G' represents a tubular tack-holder, which is preferably arranged in an inclined position with its rear end resting in a bracket, n , attached to the handle B, and with its lower end supported in a similar bracket, n' , attached to the block A, as shown. The extreme lower end of this tube rests upon or over the top of the under section of the tube 65 G, so that when the hammer is withdrawn a tack will fall by gravity into said tube.

K represents a bent operating-lever pivoted to the handle B, near the lower end thereof, in a suitable bearing-bracket, p , and extending upward to a point convenient for the hand to grasp and use. It will be seen that the said operating-lever K is bent into substantially the form of an obtuse angle, the lower straight portion of the said lever being 70 bent at a slight distance in front of the said angle (marked s) to form a transverse arm, q , which is adapted to work in the bearing or socket p , and thus I provide a strong pivotal connection between the aforesaid lever and 75 the handle B. The lower portion of this lever rests normally in a notch, n , formed in the raised standard o , which is attached to the upper curved portion of the trip-hammer. By pressing the upper end of the operating-lever 80 downward the hammer is raised from tube G, and the lever slides along in notch n until it reaches the shoulder y on said lever, when it becomes disengaged and the hammer drops, driving a tack into the floor, which in the 85 meantime has fallen from tube G' into tube G.

The operation of my invention is as follows: The device is placed in position upon the carpet with the teeth b engaging the same. The carpet is then stretched to the 90 desired point, whereupon the hammer C is elevated a slight distance by the operating-lever K, and a tack is dropped from the tube 95 G' into the spring-actuated sectional tube G, where it will be held in an upright position 100 by the springs h , which after the lower end of the hammer has been removed from the said tube G will cause the lower ends of the sections of the latter to come together and

5 clinch the tack and hold it in a position to be driven into the carpet by the descending hammer, after which the hammer is raised to its highest point until the notch in the 10 arm *o* reaches the curved shoulder *y*, formed at the end of a track, *r*, on the lower straight portion of the lever *K*. The handle of the 15 said lever *K* is then depressed a slight distance, which action releases the notch *n* of the arm *o* from the shoulder *y*, and thus trips the hammer, the latter then descending with great force upon the tack, which has in the meantime dropped from the feeding-tube into the spring-actuated sectional tube *G* by 20 the operator. It will be clearly understood that after the hammer has been tripped the notch in the arm *o*, formed on the hammer, will be disengaged from the straight engaging track portion of the operating-lever *K*. Now, 25 as the said lever is capable of lateral movement in the bearing or socket *p*, before described, it is only necessary to shift the end of the said lever into engagement with the notch *n* and the device is ready to be again operated in the manner hereinbefore described.

30 The operation of my invention will be very readily understood from the foregoing description when taken in connection with the annexed drawings.

35 It should be here observed that this tube is not a reservoir, but is intended to receive but one tack at a time, the same being fed by the operator before each blow of the hammer.

Having described my invention, what I claim is—

1. A carpet stretcher and tacker having

40 the base *A* and the handle *B*, both being provided with supporting-brackets, in combination with the tack-feeding tube *G'* and operating-lever *K*, the latter having the shoulder *y* to engage with the notch *n* of the trip-hammer, the trip-hammer, the transverse pivotal connecting-arm *q* of the discharge-tube 45 formed with spring-actuated sections for clinching and holding the tack in position to be driven by the hammer, substantially as described.

2. The combination, with the base having 50 the spring-actuated jaws to receive and hold a tack, of a spring-actuated hammer having a lug, *o*, shouldered on one side and the operating-lever bent outwardly, as shown, and having the straight portion *r* to engage the 55 lug on the hammer, substantially as specified.

3. The improved carpet stretcher and tacker herein described, consisting, essentially, of the base-block having prongs or teeth and a vertical aperture in its forward 60 end, the spring-actuated plates arranged in the said aperture to grip a tack, the inclined feed-tube leading to the said aperture, the curved spring-actuated hammer having the shouldered lug *o*, and the pivoted or hinged 65 operating-lever curved, as shown, and having the straight engaging portion provided with a tripping-shoulder, as *y*, substantially as specified.

70 In testimony whereof I affix my signature in presence of two witnesses.

HENRY B. PITNER.
